Primary Examiner — Stella Reid*Assistant Examiner* — Elizabeth J Oswecki(57) **CLAIM**

The ornamental design container for pet waste, as shown and described.

DESCRIPTION

FIG. 1 is an exploded perspective view of a container for pet waste showing my new design, the lid being removed from the body of the container for ease of illustration;

FIG. 2 is a front elevational view thereof, the rear elevational view being a mirror image of the front;

FIG. 3 is a right side elevational view thereof, the left side elevational view being a mirror image of the right side elevational view;

FIG. 4 is a top plan view thereof; and,

FIG. 5 is a bottom plan view thereof.

In the drawings, the broken lines in FIG. 1 depict portions of the design that form no part of the claim.
